WASTE RECEPTACLE OR THE LIKE

Peter E. Norquest, 2001 Hervey,
Boise, Idaho 83705

Filed Feb. 25, 1970, Ser. No. 21,612

Term of patent 14 years

Int. Cl. D7—99

U.S. Cl. D49—35

FIG. 2

FIG. 1 is a top, rear perspective view of a waste receptacle or the like, showing my new design; and

FIG. 2 is a bottom, front perspective view thereof showing the sides opposite those seen in FIG. 1 with the lid exploded away and the bottom in an open position.

I claim:

The ornamental design for a waste receptacle or the like, substantially as shown.
